UNITED STATES PATENT OFFICE.

WILLIAM H. BAKER, OF MONTREAL, QUEBEC, CANADA, ASSIGNOR TO F. WILSON FAIRMAN, OF MONTREAL, CANADA.

LOOM.

Original application filed December 17, 1921, Serial No. 523,140. Divided and this application filed January 15, 1923.

This invention relates to improvements in looms and is a division from my former application, Serial No. 523,140, filed December 17, 1921.

5 The primary object of the invention is to provide a double loom in which the lays move in opposite directions and are connected together and mounted in such a manner as to balance one another, thereby to effect a considerable saving in the amount of power required to operate the loom as compared with the operation of two single looms or a double loom having two similarly moving lays.

10 15 A further object of the invention is to provide a loom of simple, durable construction, containing fewer parts and occupying smaller space as compared with ordinary looms of the same production capacity.

20 Another object is to provide in a loom of this character an improved and simplified method of mounting picker sticks.

25 A still further object is to provide for long picker sticks, thereby to reduce the arcuate movement of the tips thereof and also to obtain a high speed of movement without increasing the movement of the picker staffs beyond that in general use.

30 In accordance with this invention there is provided a rigid frame comprising a pair of parallel lays connected at their ends by swords, which swords are pivotally mounted intermediate their ends on the loom frame. A single crank shaft connected by pitman rods to the corresponding ends of the two swords will serve to oscillate the swords about their pivotal points and cause the two lays to beat in opposite directions. The

35 40 45 single crank shaft is provided with a single driving and controlling means. The picker sticks are mounted on the lay frame so as to move with the lays in the well known manner, the sticks pertaining to one lay being anchored or secured to the other lay and extending across the frame, thereby to obtain the maximum possible length of stick and assist in reducing the arcuate movement of the end thereof.

50 In the drawings which illustrate the invention;

Fig. 1 is an end elevation of a loom constructed according to this invention, only those parts necessary to an understanding of the invention being shown.

Fig. 2 is an elevation of the left-hand side 55 of the loom shown in Figure 1.

Fig. 3 is a partial plan view of the lay frame.

Referring more particularly to the drawings, 11 designates a pair of substantially similar end frames, one of which supports a driving and brake mechanism 12 operatively connected with a crank shaft 13 extending from end to end of the loom. The frames also support a shaft or rod 14, likewise extending from end to end of the loom and supported, preferably rotatably, in bearings 15 on the ends of the loom. A pair of double-ended swords 16 are mounted intermediate their ends on the shaft 14 and are each connected at one end to the crank shaft by a pitman rod 17. The swords are preferably fixedly mounted on the shaft 14 so that when oscillated by the pitmen they will impart oscillatory movement to the shaft for the purpose of operating other parts of the loom, such as take up mechanism, (not shown). It will be understood, however, that the shaft 14 may be fixedly mounted in the end frames and the swords rotatable thereon. A pair of lay beams 18 disposed preferably parallel with one another and with the shaft 14 are rigidly connected to corresponding ends of the swords so as to form with the swords a rigid rectangular frame. Each lay beam is of any usual or suitable construction and carries reeds 19, and at the ends thereof shuttle boxes 20 and other usual or necessary 70 75 80 85 90 95 100 105 apertures. Preferably the lay beams are disposed equidistantly on opposite sides of the shaft 14 but this is not essential.

In the ordinary loom in which the lay beats in a substantially horizontal direction the shuttle runs on the lay beam and the reed is disposed in a substantially vertical plane at the back of the beam, the warp passing in a substantially horizontal plane through the reed. For various reasons it is preferred in the present construction to pass the warps in substantially vertical directions and to so mount the swords and lays that the beat is in substantially vertical direction. This necessitates the location of the reeds in substantially horizontal planes so that the shuttles run on the reeds rather than on the beams. With this disposition and movement of the lays the swords are

inclined first in one direction to the horizontal and then in the opposite direction, as will be readily seen from Figure 1. On account of this oscillation to produce the lay movement it is necessary to dispose the reeds at an angle to the longitudinal axes of the swords, so that when the sword is at its maximum inclination in either direction the reed that is lowermost will not be inclined away from the centre of the loom but will be at least horizontal or, preferably, inclined slightly downward toward the centre of the loom in order that there may be no tendency for a shuttle to slide off the side of the reed and break the warp. A slight inclination of the reeds downwardly toward the centre of the loom when in their lowermost position so as to cause the shuttles to hug the lay beams, is the preferred disposition. The outer surfaces of the lay beams are naturally normal to the planes of the reeds they carry and the lays can therefore be said to be inclined inwardly and to converge toward a line above the loom. The angular relation of the reeds and the inclination of the lay beams to the longitudinal axes of the swords will be clearly seen in Figure 1. It will be understood, however, that while the substantially horizontal disposition of the lay frame is preferred, that the invention is not thus limited but that the frame may be disposed to locate the lays one above the other so as to beat in substantially horizontal planes.

Each lay carries at the back of its shuttle boxes a bracket 21 which serves as a guide for the picker stick operating in that shuttle box and serves also for the anchorage of the picker stick operating in the corresponding box of the other lay. The picker sticks, designated 22, extend across the centre of lay oscillation making it possible to employ a long stick without positioning the lays so far apart as to make the machine of uncommercial size. This disposition of the picker sticks therefore enables the lays to be brought so close together as to make a very compact machine. The sticks are anchored to the brackets in any suitable or usual manner and are provided with the usual rocking shoes 23 bearing on the brackets and serving to reduce or eliminate arcuate movement of the stick ends in order that the pickers 24 thereon may travel in the straight line of the shuttle boxes. In a double loom the distance between the lays will usually be such that it is possible to employ longer sticks than in an ordinary loom, thus providing for greater travel and velocity of the pickers without increasing the movement of the picker staffs. This question of picker travel and speed is, however, largely a matter of the position of the lug straps 25 on the picker sticks and the positioning of the picker staffs and the design of the cams,

but it is well to note that the design of the lay frame enables these advantages of picker movement to be attained.

The picker sticks receive motion through the lug straps 25 from picker staffs 26 disposed vertically one on each side of the shaft 14 and pivotally supported at their lower ends on brackets 27 carried by the end frames. In Figure 2, while the bracket and picker staffs have been shown at only one end of the loom, it will be understood that the arrangement is duplicated at the opposite end. The picker staffs receive motion from roller cams 28 mounted on a shaft 29 operatively connected with the driving train of the crank shaft and disposed beneath the shaft 14. At either end of the loom there are two vertically disposed picker staffs, one for each of the picker sticks, disposed at opposite sides of the axis of lay frame oscillation and operated by a single roller cam 28. This location of the picker staffs close to the axis of lay oscillation enables the lug straps to be connected to the picker sticks at points where the oscillatory movement is very little, and thereby reduces the side draft on the picker sticks to a negligible amount.

In the double vertical loom illustrated the harness motion, designated 30, is disposed preferably below the lays, as indicated in Figure 1, which figure also indicates the position of the warp beams 31, whip rolls 32, sand rolls 33 and cloth rolls 34 and the warp 35 relative to the lays.

From the foregoing description it will be observed that there is provided to operate in a single machine a balanced lay frame embodying two oppositely movable lays and swords common to both lays, the whole forming a rigid framework oscillatable about a line intermediate the lays, and which framework carries the picker sticks anchored on the opposite side of the centre of oscillation from the lays to which they pertain. In addition to reducing the number of parts this arrangement provides for a perfect balancing of the lays, so that a considerable economy of power may be effected as compared with two single looms having in combination a capacity equal to the present double loom. The arrangement of the picker sticks has the advantage additional to those already enumerated, that the lug straps may be connected to the sticks at points close to the centre of oscillation where the relative lateral movement of the picker sticks and picker staffs will be very little, thereby greatly reducing the side draft on the picker sticks as compared with ordinary looms.

In the foregoing description and appended claims, unless the clear meaning of the context requires otherwise, the term "lay" is to be understood as a generic term embracing the complete organization of parts usu-

ally associated with or carried by the lay beam and not as limited to the lay beam itself.

Having thus described my invention, what

5 I claim is;—

1. In a loom, a pair of oppositely movable balanced lays and rigid connection between said lays.

10 2. In a loom, a pair of oppositely movable balanced lays and swords common to the two lays, said swords being pivotally supported intermediate their ends.

15 3. In a loom, a pair of lays disposed side by side, rigid connection between said lays, and means to move the lays oppositely to one another.

20 4. In a loom, a pair of oppositely movable lays, and oscillatable supports for both of said lays in common directly connected to the lays.

25 5. In a loom, a member pivoted intermediate its ends for oscillatory movement, and lays connected to the ends of said member for movement thereby in substantially vertical direction in arcuate paths.

30 6. In a double vertical loom, a pair of lays and connection between said lays for moving the same simultaneously in opposite directions relatively to one another with counterbalancing effect, the said connection being the sole support and path determining means of said lays.

35 7. In a double loom, a pair of lays, a rocker operatively connected between said lays for moving the same simultaneously in opposite directions relatively to one another, a crank shaft, and operative connection between the crank shaft and one end of the rocker.

40 8. In a double vertical loom, a pair of lays arranged side by side, a pair of swords pivoted intermediate their ends extending between the lays and rigidly connected to the lays, a crank shaft, and operative connection between the crank shaft and one end of each sword.

45 9. In a double vertical loom, a rockably mounted shaft, swords fixed intermediate their ends to said shafts, lays rigidly connected to the ends of the swords, a crank shaft, and operative connection between the crank shaft and one end of each sword to oscillate the swords and rock the shaft.

50 10. In a loom, a pair of lays, and rigid connection between the lays for moving the lays oppositely of one another with balancing effect.

55 11. In a loom, a pair of lays, and rigid connection between the lays for moving the lays oppositely of one another with balancing effect, and operating means connected to said rigid lay connection.

60 12. In a double vertical loom, a pair of lays, pivotally mounted swords common to and supporting both lays for up and down

movement in arcuate paths, reeds carried by the lays adapted to form shuttle supports, said reeds being disposed in such relation to the pivotal axes of the swords, that in the lowermost positions of the lays the reeds will be positioned to retain shuttles against tendency to movement laterally off the reeds by the action of gravity.

70 13. In a double vertical loom, a pair of operatively connected lays disposed on opposite sides of an axis of lay oscillation, and picker sticks associated with the lays extending across the axis of lay oscillation.

75 14. In a double vertical loom, a pair of parallel connected lays, and picker sticks associated therewith, the sticks operating with one lay having a rocking connection with the other lay.

80 15. In a loom, oscillating supports, a lay carried thereby at one side of the center on which said supports oscillate, and picker sticks associated with said lay and rockably mounted on the oscillating supports at the opposite side of the center of oscillation from the lay.

85 16. In a double vertical loom, a pair of substantially parallel lays operatively connected for oscillatory movement relatively in opposite directions about an axis disposed between them, and picker sticks associated with the lays, the sticks operating with one lay being rockably mounted on the other lay.

90 17. In a double vertical loom, a pair of substantially parallel lays operatively connected for oscillatory movement relatively in opposite directions about an axis disposed between them, and picker sticks associated with the lays, the sticks operating with one lay being rockably mounted on the other lay, and picker stick supports carried by the lays, each support serving to rockably mount the foot of one picker stick and to guide another picker stick adjacent the tip end thereof.

100 18. In a double vertical loom, a pair of parallel connected lays, and picker sticks associated therewith, the sticks operating with one lay being carried by the other lay, and picker stick supports on said lays each serving to rockably support one stick at its foot to guide another stick adjacent its tip end.

110 19. In a loom, an oscillating lay, and picker sticks associated therewith and rockably mounted on the opposite side of the axis of lay oscillation from the lay, and means to impart movement to the picker sticks connected thereto adjacent the axis of lay oscillation.

115 20. In a double vertical loom, a pair of substantially parallel lays operatively connected for oscillatory movement relatively in opposite directions about an axis disposed between them, and picker sticks associated with the lays, the sticks operating with one lay being rockably mounted on the other lay,

and means to impart movement to the picker sticks connected thereto on opposite sides of and adjacent the axis of lay oscillation.

21. In a loom, an oscillating lay, and picker sticks associated therewith and rockably mounted on the opposite side of the axis of lay oscillation from the lay, picker staffs disposed at an angle to the plane of the sticks and lay, and connections between the staffs and sticks at points adjacent the axis of lay oscillation, whereby side draught on the sticks is minimized. 10

22. In a double vertical loom, a pair of substantially parallel lays operatively connected for oscillatory movement relatively in opposite directions about an axis disposed between them, and picker sticks associated with the lays, the sticks operating with one lay being rockably mounted on the other lay, 15 picker staffs disposed on opposite sides of the axis of lay oscillation and connections between the staffs and sticks. 20

23. In a double vertical loom, a pair of substantially parallel lays operatively connected for oscillatory movement relatively in opposite directions about an axis disposed between them, and picker sticks associated with the lays, the sticks operating with one lay being rockably mounted on the other lay, 25 picker staffs at opposite ends of the lays disposed in pairs, the staffs of each pair disposed on opposite sides of the axis of lay oscillation, and connections between the staffs and the sticks of those lays on the opposite side of the axis of oscillation from the staff. 30

24. In a double vertical loom, a pair of substantially parallel lays operatively connected for oscillatory movement relatively in opposite directions about an axis disposed between them, and picker sticks associated with the lays, the sticks operating with one lay being rockably mounted on the other lay, 40 picker staffs in pairs at opposite ends of the lays, connections between the staffs and

sticks and common operating means for the staffs of each pair. 45

25. In a double vertical loom, a pair of substantially parallel lays operatively connected for movement, relatively in opposite directions, picker sticks associated with the lays, picker staffs in pairs at opposite ends of the lays, connections between the staffs and sticks, a shaft passing between the staffs of each pair and cams on said shaft, each 50 cam positioned to successively operate the staffs of one pair. 55

26. In a double loom, in combination, a movable rigid frame including a pair of lays, means for actuating said frame to produce 55 lay-movements, and picker sticks carried by the frame. 60

27. In a double loom, a pair of spaced lays arranged substantially parallel and picker sticks associated with the lays and 65 traversing the space between the lays. 65

28. In a double loom, a pair of spaced lays arranged substantially parallel and picker sticks associated with the lays, the sticks of each lay having a rocking connection 70 with the other lay. 70

29. In a double loom, an oscillatable frame including a pair of substantially parallel lays and picker sticks all carried by the said frame. 75

30. In a double loom, a frame oscillatable about an axis within itself, including a pair of substantially parallel lays disposed on opposite sides of the axis of frame oscillation, and picker sticks carried by the frame. 80 80

31. In a double loom, a frame oscillatable about an axis within itself, including a pair of substantially parallel lays disposed on opposite sides of the axis of frame oscillation, and picker sticks carried by the frame, the 85 sticks associated with each lay being carried by the other lay. 85

In witness whereof, I have hereunto set my hand.

WILLIAM H. BAKER.
